EPICYCLIC FLUID FLOW APPARATUS

Lewis Ferry Moody, Princeton, N. J.

Application August 28, 1935, Serial No. 38,162

10 Claims. (Cl. 253—148)

This invention relates generally to fluid propelling and fluid power generating apparatus of the blade type and more particularly to improved means for minimizing the possibility of friction between the blades and fluid flowing thereover, the invention being particularly applicable to hydraulic turbines, pumps and propellers wherein the hydraulic friction may be of appreciable magnitude.

10 The history of hydraulic turbine and pump practice shows a continued struggle to increase the permissible speeds of rotation of the revolving element, to make them suited to the speeds attainable in the electric generators of motors to which they are usually coupled, and to reduce the weight and cost of the machinery and surrounding structure. Particularly in adapting the machines to low heads and large water quantities the question of speed becomes of major importance, often 15 justifying a considerable sacrifice in efficiency to attain a high speed. The propeller type turbine and pump using high relative velocities between the runner blades and the water have accomplished a notable increase in rotational speed.

20 Employing these high relative velocities, however, necessitates a high surface resistance and loss of head which not only impairs efficiency, but effectually resists any effort toward further speed increases; and the attempt to reduce this 25 resistance by employing narrow blades of reduced area has been ineffective beyond a certain point and if carried too far results in cavitation, pitting and instability and loss of efficiency without material increase in speed. I, therefore, have introduced a method of eliminating a large portion of 30 this loss by a change in the whole method of action between the blades and fluid. This new principle is applicable to hydraulic turbines, pumps, reversible pump-turbines, air blowers, marine 35 propellers or any machine utilizing the interaction of moving blades and flowing fluid; but is illustrated here as applied to specific machines or elements, and particularly illustrated in a hydraulic turbine.

40 According to the principle of this invention, while the conformation of the blades remains fixed with respect to the hub of the runner or revolving element, the actual material and, therefore, the surface of each blade moves backwardly 45 with respect to the motion of the hub and of the runner as a whole, so that the relative velocity between fluid and blade surface is reduced. This is accomplished by forming the blades as pivoted circular disks properly cupped or curved in planes 50 containing the pivot axis to provide the proper

5 hydraulic contour, and mounting the pivots in bearings carried by the runner hub so that each blade is free to rotate with respect to the hub and shaft of the runner. When left free to rotate relatively to the runner as a whole, each disk will automatically endeavor to assume that speed of 10 relative rotation which will give a minimum frictional drag from the working fluid, thus minimizing the resistance opposing rotation of the runner and at the same time minimizing the disturbance set up in the flowing fluid and loss of head due to eddies.

15 The source of surface friction resistance is in the boundary layer of fluid in contact with and close to a surface along which it flows. If the 20 surface can move with the fluid this source of loss and turbulence is eliminated. Moreover, the 25 drag or tangential friction force is closely proportional to the square of the relative velocity, so that if the relative velocity is reduced to one-half its original value, the drag or frictional force is reduced to only about one-quarter of its previous amount. Consequently it is not necessary to 30 reduce the relative velocity to zero at all points; but any material reduction in velocity will be reflected in a much greater proportional reduction 35 in friction and loss of energy. The complete runner or rotating element of this invention involves an epicyclic action (sometimes termed a planetary motion)—a series of blades or disks which rotate 40 relatively to the revolving system at the same time that the system itself revolves. Any point on a blade traces in space an absolute path which is epicycloidal in character. It is, of course, necessary to modify the blade's peripheral contour 45 somewhat to make it circular, thus cutting away its outer corners farther than is usually done in the case of turbines and pumps. This is partly compensated by increasing somewhat the number of blades—say from four to six or eight, and 50 allowing considerable overlap in the inner portions near the hub, which is not objectionable. The blades are also inclined at a smaller angle, relatively to a plane normal to the runner axis, than is usual in turbines and pumps; that is, the 55 blades are given a smaller pitch than usual, in speaking of a marine propeller. This is permissible since a higher speed of runner rotation is to be attained. The new type of runner here described is particularly adapted to very high specific speeds.

Certain portions of the boundary wall of the fluid passages usually comprising portions of the stationary elements of a turbine or pump may also when desired follow the principle here de- 55

scribed, that is, they may be made freely rotatable to permit them to take up automatically a motion minimizing the wall resistance of the flowing medium. The same principle may also be applied to the conical end or other portions of the runner or propeller itself, this cone or portion being mounted on a bearing coaxial with the runner so that it is free to revolve at a speed different from that of the runner proper.

10 The principle of the invention will be better understood by referring to the following descriptions of illustrative embodiments, in which:

Fig. 1 is a sectional elevation of an axial-flow hydraulic turbine runner and surrounding elements;

15 Fig. 2 is a partial section of the runner of Fig. 1, on line 2-2 of Fig. 1;

Fig. 3 is a section of one of the blades of the runner of Fig. 1 in a plane containing the pivot axis of the blade;

20 Fig. 4 is a sectional elevation of the powerhouse containing the turbine of Figs. 1-3;

Fig. 5 is a sectional elevation of a diagonal-flow hydraulic turbine runner and surrounding 25 parts;

Fig. 6 is a sectional elevation of a horizontal-shaft pump, turbine or reversible pump-turbine;

Fig. 7 is a sectional elevation of a vertical-shaft pump.

30 In the turbine of Figs. 1 to 4 the water enters from the spiral casing 1 of usual form, passes between the stay vanes 2, pivoted guide vanes or wicket gates 3, flows through the transition space 4, runner 5 and into the draft tube 6. The head cover 7 supports the main shaft bearing 8, stuffing box 9, and guide vane operating mechanism 10. The main shaft 11 is coupled to, or continued to form, the shaft 12 of the generator 13, where it is supported by a thrust and guide bearing. At its lower end it is bolted to the hub 14 of the runner 5. This hub carries a series of inclined bearings 15 in which are rotatably supported the pivots 16 of the blades or disks 17. These blades have their outermost portions exposed to the flowing fluid which drives the runner by acting on them. Their inner portions are within the hollow hub 14 which is filled with idle water. The blades or disks pass through slots formed to receive them without touching them, a small clearance being provided. It will be understood that in passing through the dead water within the hub during their relative rotation the blades will suffer a certain amount of retarding drag, but less than the forward drag from the active flow outside, so that the blades will automatically assume a mean velocity minimizing the total drag, or balancing the forward and backward forces. Furthermore, the active surface forces near the outermost limits of the runner, 55 where the blades encounter the highest relative velocities, will exert a large moment to rotate the vanes on account of the large effective lever arm about the pivots, so that the final velocity of relative rotation will tend to accommodate it self to the rapidly moving part of the flow. That 60 part of the flow near the hub surface will be comparatively little effected by the blade rotation, but here the relative velocities and resistances are very much less than in the region of the blade "tips" or outermost portions. The net result will 65 be a material reduction in the average relative velocity between blades and flowing water, and a still greater proportional reduction in drag and loss of head.

70 75 The bearings 15 for the pivots are shown with

removable portions permitting the ready assembly or removal of the blade disks.

In Fig. 1 (not shown in Fig. 4) is illustrated the method of further reducing the resistance to flow by making the inner wall 18 of the transition space 4 movable. Although this provision is not as important as the blade rotation, since the absolute velocity of flow along this wall is much less than the relative velocity of the runner blades, it may be used in addition to reduce the wall friction opposing flow and the consequent turbulence propagated in the flow. The portion 18 is freely rotatable, supported by the bearings shown, either ball bearings as indicated or plain journal bearings.

15 In Fig. 1 the draft tube is of the spreading type with central core or cone registering with the runner. This type is advantageous when unit spacing permits its use, particularly with the large diameter hub here required. This hub diameter is of the same general proportions as in many turbines of the Kaplan or adjustable blade type, and the relatively large size has not been found prohibitive.

20 In Fig. 4 the same turbine as in Fig. 1 is shown in connection with an elbow draft tube. Here, if desired, the lower conical end 19 of the runner hub can be made freely rotatable, carried by a journal bearing on a stub shaft mounted in the bottom wall of the hub.

25 In Fig. 2, v indicates the absolute velocity of the runner hub and rotating system; q indicates the backward relative velocity of the blade disk. At any point, the effective relative surface velocity will be $v - q$, v being the relative velocity of the 30 system or of a non-rotating blade with respect to the water, or of the water with respect to the blade. If at a point in the outer portion of the blade q assumes a value of say 42.3% of v , the effective surface velocity will be 57.7% of v and the frictional drag will be only one-third of that with a fixed blade.

35 In Fig. 6 my improved runner is applied to a horizontal shaft hydraulic apparatus adapted to function either as a pump, turbine or reversible 45 pump-turbine while in Fig. 7 the runner is applied to a vertical shaft pump. The foregoing construction may embody any of the features of the other modifications, but preferably the Fig. 6 runner is the same as shown in Fig. 1, while the Fig. 7 runner is the same as Fig. 4 and accordingly carries the same reference numbers.

40 In Fig. 6 the runner or impeller 5 operates within a space between two sets of guide vanes, 20, 21. When operating as a pump, vanes 20 55 are guide vanes directing the flow to the runner and 21 are diffusion vanes decelerating the flow therefrom. When operating as a turbine, the directions of flow and runner rotation are reversed.

50 In Fig. 7, the flow is upward between the guide or stay vanes 22, through the impeller 5, and the diffusion vanes 23.

55 From the foregoing disclosure, it is seen that I have provided very effective means for minimizing frictional resistance between the more vital portions of the apparatus such as the blades or a portion of the wall forming the transition space. It will of course be understood that various changes in details of construction and arrangement of parts may be made by those skilled in the art without departing from the spirit of the invention as set forth in the appended claims.

60 I claim:

65 1. Fluid apparatus comprising, in combination, 70

75

- a rotor hub rotatable about a fixed axis and having overlapping blades directly supported by said hub, said blades normally rotating in only one direction relative to the hub during rotation thereof, and means forming a passage in which said rotor operates.
2. Fluid apparatus comprising, in combination, a rotor having a hub rotatable about a fixed axis and blades supported directly by said hub and continuously movable in one direction relative thereto during rotation thereof, and means forming a fluid passage in which said rotor is coaxially disposed.
3. Fluid apparatus comprising, in combination, a rotor hub rotatable about a fixed axis and having disc blades supported directly by said hub and individually rotatable relative thereto during rotation thereof, and means forming a fluid passage in which said rotor is coaxially disposed.
4. Fluid apparatus comprising, in combination, a rotor having a hub rotatable about a fixed axis and disc blades supported directly by said hub, means for supporting the blades for continuous rotation relative to the hub, and means forming a fluid passage in which said rotor is coaxially disposed whereby said disc blades rotate during flow of fluid thereover thereby to minimize surface friction between the blades and fluid.
5. Fluid apparatus comprising, in combination, a rotor having a hub rotatable about a fixed axis and disc blades supported directly by said hub means for supporting said discs by said hub for continuous uni-directional rotation about inclined axes, and means forming a fluid passage in which said rotor is coaxially disposed.
6. Fluid apparatus comprising, in combination, a rotor having a hub rotatable about a fixed axis and blades supported directly by said hub and continuously revoluble relative thereto during fluid flow over said blades, the opposite sides of

said blades having different contours, and means forming a fluid passage in which said rotor is coaxially disposed.

7. Fluid apparatus comprising, in combination, a rotor having a circular hub with recesses therein, disc blades having one portion disposed within said recesses and another portion projecting outwardly from the surface of said hub, and means for supporting said blades for continuous unidirectional rotation.

8. Fluid apparatus comprising, in combination, a rotor having a circular hub with recesses therein, disc blades having one portion disposed within said recesses and another portion projecting outwardly from the surface of said hub, and means for supporting said disc blades for continuous rotation in the same direction relative to said hub.

9. In a hydraulic turbine, in combination, a rotatable hub, a series of relatively flat circular disks pivotally mounted in said hub and rotatable relatively thereto about axes different from the axis of rotation of said hub; said disks passing through slots in the hub wall formed to provide small clearance around said disks, and the axis of said disks being inclined in a direction more nearly perpendicular than parallel to a plane normal to the axis of rotation of the hub.

10. In a rotary fluid apparatus, in combination, a rotatable hub, a series of relatively flat circular disks pivotally mounted in said hub and rotatable relatively thereto about axes different from the axis of rotation of said hub; said disks passing through slots in the hub wall formed to provide small clearance around said disks, and the axis of said disks being inclined in a direction at an angle to the axis of hub rotation when projected in a plane containing said hub axis, and also inclined with respect to said plane.
